Patented June 20, 1972

223,926

MASTER CONTROL PANEL FOR ALARM SYSTEMS OR THE LIKE

Robert D. Kahn, Rockville Centre, N.Y., assignor to
Fedtro, Inc., Rockville Centre, N.Y.

Filed Jan. 22, 1971, Ser. No. 109,094

Term of patent 14 years

Int. Cl. D13—03

U.S. Cl. D26—13

FIG. 1

FIG. 2

FIG. 3

FIG. 4

FIG. 5

FIG. 1 is a front isometric view showing a master control panel for alarm systems or the like according to the present invention;

FIG. 2 is a back elevational view thereof;

FIG. 3 is a top plan view thereof;

FIG. 4 is a bottom plan view thereof; and

FIG. 5 is a side elevational view thereof, taken from the right side.

I claim:

The ornamental design for a master control panel for alarm systems or the like, as shown.
